UNITED STATES PATENT OFFICE.

EDWARD THOMPSON, OF CASHTON, WISCONSIN.

VEHICLE BOLSTER WITH FOLDING STAKES.

Application filed May 15, 1923, Serial No. 639,161. Renewed September 2, 1924.

To all whom it may concern:

Be it known that I, EDWARD THOMPSON, a citizen of the United States, residing at Cashton, in the county of Monroe and State 5 of Wisconsin, have invented certain new and useful Improvements in Vehicle Bolsters with Folding Stakes, of which the following is a specification.

This invention relates to bolsters for 10 wagons and sleighs and the like, and the main object of the invention is to furnish the bolster with folding stakes in such a manner that the bolster may be lengthened or shortened as required to suit the load to 15 be carried.

In most bolsters having folding stakes, these stakes are generally attached to the bolster in such a manner that they may be folded under or alongside the same when 20 a flat bed is required in the vehicle, in which position the stakes are entirely useless.

One object of the present invention is to mount the stakes on the bolster in such a manner that they can be utilized at all 25 times. For instance, if a short bolster is required, the stakes are secured upright thereon, but when a longer bolster is needed, the stakes are folded outwardly to provide a continuation in outward direction of the 30 bolster, while auxiliary stakes may then be erected at the ends of the folding stakes.

In the accompanying drawing, one embodiment of the invention is illustrated; and—

35 Figure 1 represents a bolster provided with folding stakes forming the subject matter of the present invention; and

Figure 2 is a longitudinal section of the bolster with the stakes in erected position.

40 The bolster is denoted by reference numeral 10 and is preferably made of solid hard wood with a central opening 11 for the pintle. The bolster is preferably of square or rectangular cross section with a 45 flat upper surface as at 12 and a flat short surface on the bottom as at 13 in the middle thereof, with the two ends as at 14 tapering upwardly.

On top of each end is secured, as by 50 bolts or rivets 15, one leaf 16 of a hinge for the foldable stake 17. The outer leaf 18 of the hinge is similarly secured by rivets 19 or the like on the upper side of the stake. Each stake is in the shape of a 55 truncated pyramid with flat ends, the one end 20 being preferably of the same section

as the end 21 of the bolster 13. When in extended position, the bottom surface 22 of the stake forms a continuation in the same plane as the tapering bottom surface 12 of the end of the bolster 13.

Near the outer end of each stake is furnished an aperture 23 running perpendicularly through the same and the hinged leaf 18 and penetrating the same. These apertures 23 are intended to carry auxiliary stakes 24 when the main or folding stakes are in their extended position, as indicated by dot and dash lines in Figure 1.

Each of the folding stakes is provided 70 with a pair of arms 25 extending beyond the butt end of the stake and secured thereto by cross rivets or bolts 26. On the tapering under side 14 of the bolster is secured a flat bracket 26, secured by the same 75 bolts or rivets 15 that hold the leaf 16 of the hinge to the bolster. These brackets extend beyond the ends 21 of the bolster and terminate with a sleeve 28 formed by rolling the end of the bracket over itself 80 as best seen in Figure 2. The length of the extending arms 25 and of the extending portion of the bracket 27 is such that with a retaining bolt 29 inserted through 85 openings provided in the ends of the arms and running through the sleeve 28, it will secure the stake 17 in erected position at substantially right angles to the top face 12 of the bolster.

In order to use the stakes as extensions to 90 the bolsters, the bolts 29 are removed and the stakes folded down as seen at the left end of the bolster in Figure 1, and the bolt is again inserted through the openings in the arms 25 and through a corresponding 95 opening 30 at each end of the bolster. In this manner, the stakes are rigidly secured either in upright position, as seen in Figure 2, or in folded position forming the bolster extensions, as seen in Figure 1 at the 100 left end of the bolster.

Having thus described the invention, what is claimed as new is:

1. The combination with a vehicle bolster, 105 of folding stakes therefor; a hinge for each stake having one leaf rigidly secured to the upper side of the stake and its other leaf similarly secured to the top face of the bolster, and means for holding the stake selectively in erected and folded positions, 110 the latter providing an extension for the bolster; said means including arms secured

to the stake and projecting to one end thereof, a bracket secured on the under side of the bolster and projecting beyond the end thereof, said arms having apertures, a sleeve provided at the extreme outer end of said bracket, and a bolt engaging in said apertures and said sleeve.

2. The combination with a vehicle bolster, of folding stakes therefor; a hinge for each 10 stake having one leaf rigidly secured to the upper side of the stake and its other leaf similarly secured to the top face of the bolster, and means for holding the stake selectively in erected and folded positions, the 15 latter providing an extension for the bolster; said means including arms secured to the stake and projecting to one end thereof, a bracket secured on the under side of the bolster and projecting beyond the end thereof, said arms having apertures, a sleeve provided at the extreme outer end of said bracket, a bolt engaging in said apertures and said sleeve, and an aperture furnished in the end of the bolster and adapted to register with the apertures in said arms 20 and to receive said bolt with the stake in extended position, said stakes being provided with openings for auxiliary stakes.

3. The combination with a vehicle bolster, of folding stakes therefor; a hinge for each 25 stake having one leaf rigidly secured to the upper side of the stake and its other leaf

similarly secured to the top face of the bolster, and means for holding the stake selectively in erected and folded positions, the latter providing an extension for the 35 bolster; said means including arms secured to the stake and projecting to one end thereof, a bracket secured on the under side of the bolster and projecting beyond the end thereof, said arms having apertures, a sleeve 40 provided at the extreme outer end of said bracket, a bolt engaging in said apertures and said sleeve, and an aperture furnished in the end of the bolster and adapted to register with the apertures in said arms 45 and to receive said bolt with the stake in extended position, said stakes being provided with openings for auxiliary stakes.

4. The combination with a vehicle bolster having flat ends; of folding stakes therefor 50 provided with corresponding flat abutting ends, hinges for said stakes securing the same at the respective ends of the bolster and to the upper side thereof, means for securing the stakes selectively in upright or extended positions; said stakes, when in extended position, engaging with their flat ends, the corresponding flat ends of the bolster thus providing a continuous beam.

In testimony whereof I affix my signature.

EDWARD THOMPSON. [L. S.]
